UNITED STATES PATENT OFFICE

GEORGE H. CARLSON, OF ROCKFORD, ILLINOIS, ASSIGNOR TO ELSTROM, CARLSON & CO., OF ROCKFORD, ILLINOIS, A CORPORATION OF ILLINOIS

EXERCISING MACHINE

Application filed October 10, 1928. Serial No. 311,501.

The invention relates generally to exercising machines of the type employing power means to produce an oscillatory motion or vibration which is applied to the various muscles of the human body by suitable means such as a belt attached to the machine and held in contact with the muscles to be exercised.

10 A general object of the invention is to produce an improved machine of this character embodying means for varying both the speed and amplitude of vibration, which means are operable by manual control members extending into convenient reach of the operator 15 while in a standing position.

Another object of the invention is to provide an improved machine of this character which is extremely rugged and positive in its operation.

20 Another object is to provide such a machine embodying novel means whereby the user may vary the oscillatory stroke of the machine by very fine graduations.

Another object is to provide an exercising 25 machine having novel and improved means for starting and stopping the oscillatory motion thereof.

Another object is to provide a new and improved device for transforming the constant 30 rotary motion of the driver into an oscillatory motion of the vibrating element.

A further object is to combine in a simple unit the means for transforming rotary motion into oscillatory motion and the means 35 for gradually varying the oscillatory stroke produced thereby.

Other objects and advantages will become apparent from the following description taken in connection with the accompanying 40 drawings in which:

Fig. 1 is a front elevational view partially in section of an exercising machine embodying the preferred form of the invention.

Fig. 2 is a fragmental sectional view taken 45 along the line 2—2 of Fig. 1.

Fig. 3 is an enlarged fragmentary sectional view taken along the line 3—3 of Fig. 2 showing the parts in different positions.

50 Fig. 4 is a fragmental side elevation of

the machine as viewed from the line 4—4 of Fig. 1.

Fig. 5 is a fragmental sectional view taken along the line 5—5 of Fig. 2.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

For the purposes of this disclosure the invention is embodied in an exercising machine having an upright standard 10 supported on a base 10^a, the standard preferably being tapered and of circular cross section, thus serving to support and house a vertical shaft 11 which is rotatably mounted within the standard 10 in a bearing 12 at the top of the standard. The upper end of the shaft projects out of the top of the standard and has a cross bar 13 mounted thereon for movement thereby. Thus an oscillatory motion of the shaft 11 will move the ends of the cross bar 13 back and forth and a pair of hooks 14 are provided at the ends of the bar 13 to receive a suitable applicator such as a strap 15 through which this movement of the cross bar may be utilized for exercising the muscles of the human body. As shown in Fig. 2 the platform 10^a extends forwardly of the standard 10 and may if desired serve as a platform upon which the user may stand so as to render the device more stable.

For the purpose of effecting in oscillatory movement of the cross bar 13 the embodiment of the invention herein illustrated is provided with an electric motor 16 adjustably mounted upon the base 10^a rearwardly of the standard 10, and its motion is communicated to the vertical shaft 11 by a suitable driving connection therebetween.

In the present instance this driving connection includes a horizontal shaft 17 rotatably supported above the motor 16 and having one end adjacent the lower end of the

vertical shaft 11. For purposes of economy and neatness the shaft 17 is preferably supported and housed by a tubular casing or housing 18 having one end opening into the lower end of the hollow standard 10 and secured thereto by means of bolts 19 extending through a flange 20 on the casing 18 and engaging the standard 10.

The casing 18 projects laterally from the bottom of the standard 10 and has a wall 21 closing its outer end and arranged to rotatably support one end of the shaft 17 in fixed axial position through the medium of a ball bearing 22. The other end of the shaft 17 projects into an axial bore 23 formed in a rotatable hub member 24 which is positioned within the casing 18 and which hub in the present embodiment serves to support the end of the shaft 17 upon which it is mounted. To this end the hub 24 is rotatably supported by a ball bearing 25 having an inner race 26 secured to the hub by a nut 27 and an outer race 28 fitting within and supported by the walls of the casing 18.

The horizontal shaft 17 and the hub 24 are splined together as at 29 so that the hub will be rotated by the shaft and means is provided connecting the hub 24 to the vertical shaft 11 operable upon rotation of the shaft 17 to impart an oscillatory motion to the vertical shaft 11. This means preferably comprises an arm 30 connected at one end to the vertical shaft 11 for pivotal movement about a horizontal axis and having its other end engaging the hub 24 eccentrically of its axis of rotation so as to be moved in a circle by rotation of the hub.

For the purpose of pivotally connecting the arm 30 to the vertical shaft 11 a yoke 31 (Fig. 1) is preferably provided having two horizontally spaced vertical members 32 connected by an upper cross member 33 in which the lower end of the shaft 11 is non-rotatably secured. A lower cross member 34 has a stub shaft 35 therein which is rotatable in a bearing 36 mounted in a cross bar 37 in the vertical standard 10. The end of the arm 30 is positioned between the two vertical members 32 and a wrist pin 38 extends through suitable horizontal bores formed in the three parts.

Thus when the free end of the arm 30 is moved in a circle due to its eccentric engagement with the hub 24, the horizontal components of the circular motion of the free end of the arm 30 will be transmitted to the vertical shaft 11 and will oscillate the shaft back and forth about its vertical axis (as shown in Fig. 3) in an amount which is dependent upon the eccentricity of the point at which the arm 30 engages the rotating hub 24.

In machines of the character herein shown, it is desirable to have a variable oscillatory motion and for this reason means is provided in the present embodiment whereby the ec-

centricity of the point of engagement of the arm 30 and the hub 24 may easily be varied within certain limits during the operation of the device. To this end a guide is formed on the hub 24 positioned at an angle to the axis of rotation thereof and adapted to be operatively engaged by the end of the arm 30 at any point therealong. This guide is preferably in the form of an angular bore 39 entering into the hub 24 from a point on one end adjacent its axis of rotation and extending angularly into the hub toward the other end of the hub and toward the periphery thereof. The arm 30 extends into the bore 39 and to permit relative rotative movement therebetween a ball bearing 40 is secured at the end of the arm 30 to engage the sides of the bore 39.

For the purpose of varying the point of engagement of the arm 30 with the bore 39 the hub 24 is slidable longitudinally of the shaft 17 and the outer race 28 of the bearing 25 is slidable along the walls of the casing. Thus when the hub is in the position shown in full lines in Fig. 2 the arm 30 engages the hub at a point of maximum eccentricity which will produce a maximum oscillation of the vertical shaft 11 while if the hub 24 is positioned as shown in dotted outline in Fig. 2, the arm 30 engages it at a point of minimum eccentricity and the resulting oscillatory motion will be correspondingly less.

When the hub 24 is moved relatively to the arm 30 the angular relation of the bore 39 and the arm 30 is varied and to take care of this variation, the outer race of the bearing 40 has a spherically shaped outer surface which engages the bore 39 through a sleeve 41 which has a correspondingly shaped interior surface.

Means is provided for moving the hub 24 gradually between the two positions shown in Fig. 2 during the operation of the device and this means preferably comprises a lever 42 (Figs. 2 and 5) horizontally pivoted in a housing 43 on the horizontal casing 18 and engaging an annular groove 44 formed in the hub 24 so that movement of the lever 42 about its pivot will serve to move the hub 24 along the shaft 17. To maintain the hub 24 in adjusted position, a pressure plate 44^a is provided within the housing 43 mounted on two transverse pins 45 and pressing the lever 42 by means of springs 45^a into frictional engagement with one wall of the housing 43.

The lever 42 has an operating handle 60 integrally formed therewith which extends forwardly of the machine along one side of the support 10 so that it may easily be reached by a person in a standing position in front of the machine.

The connection between the motor 16 and the shaft 17 preferably embodies means for imparting different speeds to the shaft 17 and for starting and stopping the rotary motion

thereof during the continued operation of the motor. To this end a pulley 46 is non-rotatably secured on the end of the shaft 17 outside of the casing 18 and a pair of pulleys 47 and 48 are secured on the motor shaft 49 for rotation thereby. An endless belt 50 passes over the upper pulley 46 and beneath either the pulley 47 or 48, whereby the shaft 17 may be rotated.

10 The pulleys 47 and 48 are of different sizes so as to provide two different speeds of rotation for the shaft 17 and to facilitate the selective engagement of these pulleys with the belt 50, the motor 16 is inclined so as to permit vertical movement and movement longitudinally of its axis. This mounting in the present instance comprises a shaft 51 rotatably and slidably supported near its ends by a lug 52 on the standard 10 and a bracket 53 on the base 10^a. A plate 54 is secured on the shaft 51 for rotation therewith and the motor 16 is fastened by suitable means to this plate 54 so that by a rocking movement of the shaft 51 the motor may be lifted out of engagement with the belt 50. Thus the weight of the motor serves to tighten the belt during operation and a handle 55 is fixed on the shaft 51 whereby the shaft 51 may be rocked to engage or disengage the belt 50 to start or stop the oscillation of the vertical shaft. The handle 55 also extends upwardly so as to be within easy reach of an operator in a standing position.

Since the shaft 51 is slidable, the motor 16 may be shifted longitudinally while it is in its elevated position to selectively engage the pulleys 47 and 48 to provide different speeds of oscillation.

From the foregoing it will be apparent that the invention provides an exercising machine of an extremely rugged character embodying convenient and easily operable means for varying the oscillatory stroke thereof. It will also be apparent that the motor mounting provided is of special advantage since it is economical of construction and provides both for varying the speed of the device and for starting and stopping the device during the operation of the motor.

It will also be apparent that the invention provides new and improved means for transforming rotary motion to oscillatory motion, which means is economical of construction and rugged in use.

55 I claim as my invention:

1. An exercising machine having, in combination, a housing, a driven shaft journaled therein having one end adapted to support an applicator, a second housing opening into said first housing and disposed at an angle thereto, a driving shaft in said second housing having one end journaled in a wall of said second housing, a hub member slidably splined on the other end of said driving shaft and rotatably and slidably engaging the sides

of said second housing whereby to rotatably support the end of said shaft, said hub having a bore formed therein extending from a point near its axis and adjacent the open end of said second housing into said hub at an angle to its axis, an arm having one end extending into said bore and engaging the sides thereof and the other end attached to said driven shaft for pivotal movement about an axis perpendicular to the axis of said driven shaft, and means for sliding said hub member longitudinally of said driving shaft and said second housing whereby to change the point of engagement of said arm with said bore.

2. In a machine having a driven shaft to be oscillated, a driving shaft at an angle thereto, adjustable means for connecting said driving shaft with said driven shaft operating to convert rotary motion in said driving shaft to oscillatory motion in said driven shaft, said means including a guide slidably mounted on said driving shaft for rotation therewith and disposed at an angle to the axis of said driving shaft, an arm, one end of which is adapted to operatively engage said guide to be moved in a circle by the rotary motion of said driving shaft, the other end of said arm being pivotally connected to said driven shaft to communicate oscillatory motion thereto, means adapted to move said guide relatively to said arm to regulate the movement of said arm and so regulate the angle of oscillation of said driven shaft.

3. An exercising machine comprising, in combination, a frame, a shaft mounted for oscillatory movement in said frame, an arm having one end connected to said shaft for pivotal movement about an axis perpendicular to the axis of said shaft, said arm projecting rearwardly from said shaft, means operable to move the rear end of said arm in a circle, said means comprising a rotatable hub, angular guide means on said hub, means connecting the end of said arm to said angular guide means, and means for moving said hub to vary the relative position of said hub and said arm.

4. An exercising machine having, in combination, a shaft to be oscillated and to which an exercising device may be attached, a rotatable driving shaft, and means for connecting said first shaft and said driving shaft to produce said oscillating motion, said means including a member splined to and movable axially upon said driving shaft and having a guideway whose axis describes an angle with the axis of said rotatable driving shaft, an arm having means on one end adapted to engage said guideway and to rotate therewith, and means on said first shaft supporting the other end of said arm, such last mentioned means permitting independent movement of said arm relatively to said first shaft.

in a plane perpendicular to the plane of oscillation thereof.

5. In an exercising machine, the combination of a shaft mounted for oscillatory movement, an arm having one end connected to said shaft for pivotal movement about an axis extending transversely of said shaft, means operable to move the other end of said arm in a circle about an axis perpendicular to said shaft whereby to oscillate said shaft, and means operable by the user during operation of the machine to vary the diameter of the circle through which the end of said arm is moved whereby to vary said oscillatory motion.

6. In a machine of the class described having a movable exercising means and driving means therefor including a belt, the combination of a motor having a shaft and a plurality of pulleys fixed thereon adapted to engage and drive said belt, and means whereby said motor may be moved perpendicularly to and longitudinally of its axis to selectively engage any one of said pulleys with said belt, said means including a rock shaft capable of rotary or longitudinal movement, and means eccentrically fixing said motor to said rock shaft for movement therewith.

7. In a machine of the class described having a movable exercising means and driving means therefor including a belt, the combination of a motor having a shaft, a plurality of pulleys on said shaft adapted to engage and drive said belt, and means whereby said pulleys may be adjustably moved in planes parallel or perpendicular to the longitudinal axis of said shaft to effect driving connections between said belt and any one of said pulleys.

40. 8. In an exercising machine, the combination of a rotatable driving element, an oscillatory driven element, and means connecting said elements operable to transform rotary motion of said driving element into oscillatory motion in said driven element, said means comprising a member having one end pivotally connected to said driven element, means on said driving element engaging the other end of said member to maintain said member with its axis at an angle to the axis of rotation of said driving element and operable to move said end in an orbital path, said last mentioned means being shiftable relatively to said driving and driven elements parallel to the axis of rotation of said driving element during rotation thereof to vary the angular relation of said axes.

60. 9. In an exercising machine, the combination of an oscillatory driven element, a pivotally mounted member connected to said element to effect movement thereof about the axis of oscillation of said element, said member having an idling movement about an axis perpendicular to the first mentioned axis,

a rotary driving element, a part rotating with said element and having thereon means inclined to the axis of said driving element and providing a slid able engagement with the free end of said member to effect movement of said free end through an orbital path when said driving element is rotated, and means for moving said part relative to said driven element and said driving element to vary the relation of said member to said inclined means and thereby vary the angular relation between the axis of said driving element and said member to control the size of the orbital path of the latter.

10. In an exercising machine, the combination of a rotary driving element, a member having one end operatively connected to said driving element eccentrically of the latter whereby rotation of said driving element will move said end of said member through an orbital path, an oscillatory driven element pivotally connected to said member to receive motion therefrom, the axis of such pivotal connection being perpendicular to the axis of oscillation of said driven element, and means shiftable with respect to said driving element and said driven element while said parts are in motion arranged to vary the relationship of said member to one of said elements and thereby vary the degree of oscillation which said member imparts to said driven element.

In testimony whereof, I have hereunto affixed my signature.
